UNITED STATES PATENT OFFICE.

CHARLES H. PAYNE, OF SODDY, TENNESSEE, ASSIGNOR OF ONE-THIRD TO JOHN J. CLIFT, OF SODDY, TENNESSEE.

MINE-DOOR.

1,335,255.

Specification of Letters Patent. Patented Mar. 30, 1920.

Application filed October 11, 1919. Serial No. 329,902.

To all whom it may concern:

Be it known that I, CHARLES H. PAYNE, a citizen of the United States, residing at Soddy, in the county of Hamilton and State 5 of Tennessee, have invented certain new and useful Improvements in Mine-Doors, of which the following is a specification.

The invention relates to appliances for use in mining operations and more particularly 10 to means for confining the air to the portion of the mine being worked thereby conserving the fresh air and minimizing the cost of operation. Specifically considered the invention relates to mine doors which are 15 adapted to be automatically operated by the passage of the cars to and from the shaft, the construction being such that the door is automatically opened from either approach and automatically closes after the car has 20 passed by the point at which the door is set up.

The drawings illustrate a preferred embodiment of the invention. However, it is to be understood that in adapting the same 25 to meet different conditions, various changes in the form, proportion and minor details of construction may be resorted to without departing from the nature of the invention as claimed.

30 Referring to the accompanying drawings:—

Figure 1 is a top plan view of a portion of a railway such as commonly employed in mines showing a door and actuating means 35 therefor in cooperative relation therewith.

Fig. 2 is a vertical longitudinal section on the line 2—2 of Fig. 1 looking in the direction of the arrows.

Fig. 3 is a vertical longitudinal section on 40 the line 3—3 of Fig. 1, viewed in the direction of the arrows.

Fig. 4 is a vertical transverse section on the line 4—4 of Fig. 1 looking to the left as designated by the arrows.

45 Figs. 5 and 6 are sectional details on the lines 5—5 and 6—6 respectively of Fig. 1, showing the parts on a larger scale.

Corresponding and like parts are referred to in the following description and indicated in the several views of the drawings, 50 by like reference characters.

The railway illustrated is of ordinary construction such as commonly provided in mines and comprises a continuous track 1 55 and an interrupted track 2, the latter con-

taining a movable rail section 3 which is de- 60 pressible and normally held elevated by means of springs as indicated at 4 in Fig. 4. The movable rail section 3 is provided at opposite ends with short rail sections 5 which constitute connecting means between the fixed rail 2 and the movable rail 3. The short sections 5 normally occupy an inclined 65 position as indicated most clearly in Fig. 2. Links 6 form connecting means between the several sections 2 and 3 of the interrupted rail. The depressible rail section 3 is adapted to be automatically operated by the weight of the car passing thereover and is of such a length as to admit of the door being 70 operated from either approach and in such a manner as to provide for the passage of the car without interference between the car and the door or any part of the door actuating mechanism. The movable rail section 75 3 is so mounted that weight applied to either end thereof will cause a depression of the rail so as to operate the door actuating means and effect an opening of the door in advance of the car, said door automatically 80 closing in the rear of the car after the same has cleared the movable rail.

The movable rail is provided in the length of the railway at the point where the door is required to be located and a suitable 85 frame work is erected midway the length of the movable rail and constitutes supporting means for the door. This frame work comprises uprights 7 and upper cross piece 8 and a lower cross piece 9 the latter ex- 90 tends beneath the rail comprising the track. Suitable braces 10 are disposed at opposite sides of the frame work and connect at their inner upper ends with the cross piece 8. The door comprises two members 95 or leaves 11 and 12 which are hinged at their outer vertical edges to the frame work adjacent the upright 7. The leaves or members comprising the door may be of any desired construction and the doors are of 100 such width as to overlap at their inner opposing edges as shown most clearly in Fig. 1. The doors are mounted so as to swing to open positions in opposite directions. That is to say when one of the leaves of 105 members 11 swings to the right, the companion member or leaf swings to the left. The two members or leaves of the door are connected for synchronous movement by means of a rod 13 which is connected at 110

one end to an arm 14 projecting outwardly from the axis of the member 11 and at its opposite end to a bracket 15 at a point inwardly from the axis of the member 12. As a result of this arrangement movement imparted to one of the leaves or members 11 or 12 is transmitted to the other member or leaf so that both members swing in unison in opposite directions.

10 A bell crank lever is located at one side of the track and comprises a longitudinally disposed arm 16 and a transversely arranged arm 17. The transverse arm 17 is connected with the leaf or member 12 by means of a keeper 18 the latter being disposed near the inner edge of the member 12. This bell crank lever is normally held in a given position by means of a contractile helical spring 19 which is connected at one end to the arm 16 and at its opposite end to a lever 20 which is pivotally mounted intermediate its ends on a suitable support at one side of the track. The opposite end of the lever 20 is adjustably connected with the adjacent brace 25 as indicated at 21 whereby the tension of the spring 19 may be adjusted as required. A chain or cable 21 is connected at one end to the arm 16 of the bell crank lever and passes over guide pulleys 22 and 30 is provided in its length with a contractile helical spring 23. A bell crank 24 is interposed in the length of the chain or cable 21. An operating lever 25 has an end of the chain or cable 21 adjustably connected thereto. By manipulating the lever 25 the bell crank 16-17 may be operated to swing the leaves or members of the door into open position, against the tension of the spring 19. When the lever 25 is released the leaves 40 of the door are closed by the action of the spring 19. The spring 23 compensates for any sudden pull upon the chain or cable 21 thereby preventing a too rapid movement of the door by a sudden pull upon the chain 45 or cable 21.

At one side of the track is located a plurality of standards 26 in which are mounted guide pulleys over which passes the chain or cable 21. A plurality of bars 27 is disposed transversely of the track. These bars project at one end beyond the movable rail section 3 and their outer ends receive pulleys 28 which engage the upper side of the chain or cable 21 at points intermediate the standards 26. The bars 27 are loosely connected at one end to the rail 1 so as to receive a pivotal movement and are connected with the movable rail section 3 to operate therewith. By reason of the disposition of 50 the parts the outer ends of the bars 27 provided with the pulleys 28 are depressed when the rail section 3 is moved downwardly thereby deflecting the chain or cable intermediate the standards 26 with the result 55 that the bell crank 16-17 is operated and

the door thrown into open position. The bars 27 may be connected in any manner to the rails 1 and 3. The extreme bars 27 are provided with short cross bars 29 which sustain the vertical thrust of the expandible 70 spring 4.

The short rail sections 5 are connected with the rail 1 by means of ties 30. The end of the tie 30 adjacent the rail 1 is formed with an opening to receive a strap 31 which is made secure at its upper end to the rail 1 and at its lower end to a block or chair 32. This is shown most clearly in Fig. 5. The opposite end of the tie 30 is attached to the rail sections 5 in the manner indicated in 80 Fig. 6. The end of the tie 30 passes beneath the rail section 5 and is formed with a projection 33 which engages the outer side of the rail section 5. A bolt 34 connects the tie 30 with the inner flange of the rail section 5. 85

When a mine door embodying the invention is installed it appears substantially as shown in the accompanying drawings. The movable rail section 3 is normally held elevated by means of the springs 4 and the leaves or members 11 and 12 of the door extend across the track and have their inner edges overlapped. When a car approaches the door in either direction it exerts a downward pressure on the movable rail section 3 95 thereby depressing such rail section and the outer ends of the bars 27. This action results in exerting a pull upon the chain or cable 21 whereby the bell crank 16-17 is operated and the leaves of the door thrown 100 into open position. After the car passes by the door and clears the movable rail section the latter is elevated and the parts assume a normal position. It will be understood that the action of the door in opening and closing 105 is wholly automatic, being controlled by the weight of the car as it passes over the movable rail section of the track.

Having thus fully described my invention what I claim as new and desire to secure by 110 Letters Patent, is:—

1. In combination a mine door, a track including a depressible rail section, a flexible operating member having connection with the door to effect movement thereof, means 115 for supporting a portion of the operating member in elevated position, and means connected with the depressible rail section to move therewith and effect a deflection of the operating member between its supporting 120 means to cause a pull thereon to open the mine door.

2. In combination, a track including a depressible rail section, a mine door, an operating chain having connection with the mine 125 door, spaced supporting means for holding a portion of the operating chain in elevated position and means connected with the depressible rail section and adapted to engage the operating chain intermediate the said 130

supporting means whereby to effect a pull on said operating chain when the depressible rail section is moved downward.

3. In combination, a track embodying a depressible rail section, a door normally closing the space above the track, an operating chain, connecting means between the operating chain and door, spaced supports for holding a portion of the operating chain in elevated position, and a bar extending transversely of the track and connected with the depressible rail section to move therewith and engaging the operating chain intermediate the said spaced supporting means 15 therefor.

4. In combination, a track including a depressible rail section, a door for closing the space above the tracks, a bell crank lever

having one of its arms connected with the door, an operating chain connected with the other arm of the bell crank lever, a spring normally exerting a pressure on the bell crank lever to hold the door in closed position, means for varying the tension of the spring, a compensating spring in the length of the operating chain, and a bar projecting laterally from the depressible rail section and engaging the operating chain to exert a pull thereon when the depressible rail section is moved downward.

In testimony whereof I affix my signature in presence of two witnesses.

CHARLES H. PAYNE.
